(57) CLAIM

The ornamental design for a bottle, as shown and described.

DESCRIPTION

FIG. 1 is a perspective view of the bottle;
FIG. 2 is a front elevational view of the bottle;
FIG. 3 is a rear elevational view of the bottle;
FIG. 4 is a right side elevational view of the bottle the opposite side of which is a mirror image;
FIG. 5 is a top plan view of the bottle; and,
FIG. 6 is a bottom plan view of the bottle.

The dot-dash broken lines in the drawings define the bounds of the claim and form no part thereof.

1 Claim, 5 Drawing Sheets
